United States Patent Office

Des. 196,566
Patented Oct. 15, 1963

196,566

CANOPY

Victor F. Christ-Janer, Frogtown Road,
New Canaan, Conn.

Filed Dec. 13, 1962, Ser. No. 72,843

Term of patent 14 years

(Cl. D13—1)

FIG. 1

I claim:

The ornamental design for a canopy, as shown and described.
